JOHN R. POWELL, OF PLYMOUTH, PENNSYLVANIA.

BLASTING-CAP AND CARRIER THEREFOR.

1,081,772.

Specification of Letters Patent. Patented Dec. 16, 1913.

Application filed May 26, 1913. Serial No. 769,919.

To all whom it may concern:

Be it known that I, JOHN R. POWELL, a citizen of the United States, residing at Plymouth, in the county of Luzerne and State of Pennsylvania, have invented a new and useful Blasting-Cap and Carrier Therefor, of which the following is a specification.

This invention has reference to improvements in blasting caps and carriers therefor, 10 and is designed to provide a means whereby the employment of blasting caps may be rendered safe.

Ordinarily blasting caps are in the form of elongated copper tubes closed at one end 15 and containing a quantity of fulminate of mercury, the caps being usually about an inch and a half, more or less, in length. Under the ordinary practice these caps must be attached to the fuses and it is customary 20 for a miner to carry a quantity of caps and when ready to set off a blast a suitable length of fuse is cut and introduced into the open end of the cap which is left open for such a purpose, and then made fast to 25 the fuse in any convenient way, it being not infrequent for a miner to bite the cap on to the fuse, and this has frequently resulted in serious and fatal accidents. Again, the dynamite or other explosive employed is 30 often located at the end of a bore which may be four or more feet in depth, and consequently under the ordinary practice the fuses must be long enough to reach to the accessible end of the bore, wherefore the 35 cost of the cap and fuse is considerable and is borne by the miner.

In order to save the long length of fuse an iron blasting tube may be employed and is introduced into the bore after the charge 40 is in place, and the cap is located at the end of the tube adjacent to the charge, whereupon the cap is exploded by the use of a squib which may be introduced into the accessible end of the tube and lighted and 45 after a time powder carried by the squib becomes ignited and causes the squib to travel to the inner end of the tube where it will ignite the cap and the explosion of the latter causes the explosion of the dynamite 50 or other charge. The blasting tube method of providing a way for the squib to traverse is advantageous, and the present invention has to do with a cap structure which may be adapted to the tube in a manner which 55 will prevent displacement of the cap, and the arrangement is such that the cap is far

more liable to be ignited than are the caps as ordinarily used under like circumstances.

The invention further contemplates a cap and carrier or support therefor which may 60 replace the blasting tube, and at the same time may be so arranged as to provide for a way or course for the squib.

In accordance with one form of the present invention there is provided a cap having 65 an exterior wrapping, or sheath, which may or may not be longer than the cap, and which may or may not have a charge of powder therein in addition to the usual fulminate of mercury in the cap or detonator. 70 The outer covering or sheath for the cap is made tapering at the end remote from the active or fulminate end of the cap, so as to wedge in the inner end of the blasting tube when used, or in one end of a short tube 75 which may act as a carrier for the cap, and this short tube may have applied thereto when introduced into the drill hole, or may have permanently applied thereto, an exterior bushing serving as an inner abutment 80 for tamping material, and protecting the cap from injury during tamping. When the short tube is used a blunt needle rod is employed with the thinner end introduced into the outer end of the tube to thereby 85 constitute a core around which the tamping material may be forced, so that on the withdrawal of the needle rod there is left a small bore or passageway along which the squib may travel to the short tube and there set 90 fire to the fulminate in the cap or to a powder charge carried by the outer sheath of the cap.

The invention will be best understood 95 from a consideration of the following detailed description, taken in connection with the accompanying drawings forming a part of this specification, with the further understanding that while the drawings show a practical form of the invention, the latter is not confined to any strict conformity with the showing of the drawings, but may be changed and modified so long as such changes and modifications mark no material 100 departure from the salient features of the 105 invention.

In the drawings:—Figure 1 is a more or less schematic sectional view on a large scale of a drill hole presumed to be made in the rock or other material to be blasted and 110 showing a cartridge or charge, a cap, a blasting tube, and a squib in place. Fig. 2

- is a similar view of the inner end of the bore showing the short-tube carrier for a cap and its sheath and also showing the smaller blunt end of a needle bar in position to act as a core for tamping material. Fig. 3 is a view similar to Fig. 1 but showing the construction illustrated in Fig. 2 with the tamping material in place. Fig. 4 is a view of a needle bar modified for use in connection with the present invention. Fig. 5 is a displayed view of a sheet of material from which the sheath of a cap structure may be made. Fig. 6 is a view of such a sheath.
- 15 Referring to the drawings, there is shown a cap 1 which may be of the character usually employed in blasting, and this cap is indicated as containing a mass 2 of detonating material which is customarily fulminate of mercury. The cap is permanently closed at one end, as indicated at 3, and is open at the other end, as shown at 4 in Fig. 1. Such cap is ordinarily applied to one end of a length of fuse long enough to reach 20 from the accessible end of a drill hole in the rock or coal or other material and indicated at 5 in the drawings, to the cap 1, the active end of which latter is introduced into one end of a casing 6 representing the 25 casing of a charge indicated at 7, which latter may be dynamite or permissible powder or any other suitable explosive. Of course, ordinary black powder may be used, but the use of such powder is objectionable, 30 especially in gaseous mines, because the powder makes a great deal of flame, while dynamite and permissible powder do not have this objectionable characteristic.
- In accordance with the present invention 35 the cap 1 is inclosed in a sheath 8 which may be of substantially the same length as the cap, as in the showing of Fig. 1, or may be considerably longer than the cap as indicated in Fig. 2, and in the latter case 40 the sheath where it projects beyond the cap may be filled with powder, indicated at 9, this powder readily igniting under circumstances to be described, and so setting off the 45 detonating material within the cap.
- 50 Considering the arrangement shown in Fig. 1, there is provided a blasting tube 10 of an external diameter to enter one end of the casing 6 of the dynamite or other cartridge after the usual filling at that end 55 of the cartridge has been displaced to permit the introduction of the detonating cap. This tube 10 is made long enough to extend to the outer end of the drill hole 5, so as to be readily accessible.
- 60 It has been proposed heretofore to use a blasting tube such as indicated at 10 and to have this tube partially inclose the cap 1 where the latter enters the charge, but the cap does not snugly fit the tube and consequently there is a liability, especially when

the hole 5 inclines, for the cap to slip down the tube toward the outer end and possibly become lodged therein at a considerable distance from the charge to be exploded. Under these circumstances there is no certainty but that such a contingency may happen at any time and the cap be exploded at so great a distance from the charge as to fail to ignite the latter. To overcome this objectionable feature the sheath 8 is provided, making the commercial cap of an exterior diameter which will permit it to be lodged in one end of the tube 10 in a manner whereby it cannot possibly move into the tube and when once positioned with respect to the charge will remain in such position until exploded. To bring about this arrangement the cap has wound thereon a sheet 11 of paper shown separately in Fig. 5, which sheet is long enough in one direction to wrap a sufficient number of times about the cap to bring the external diameter of the sheath 8 made of the paper sheet a little greater than the internal diameter of the tube 10. The web 11 which may be made of waterproof paper or other suitable material, is not of the same width throughout, but has cut away portions near the ends forming bevel edges 12, 13, respectively, so that when the web is wound around the cap one end of the sheath is of lesser external diameter than the other, giving to this end of the sheath a taper, the smallest diameter of which is less than the internal diameter of the corresponding end 90 of the tube 10, so as to readily enter thereinto, but that portion of the end of the sheath not including the beveled edges 12 and 13 is of full diameter which is too great to enter the tube. Because of this 95 the sheath will tightly wedge in the tube against any possibility of accidental displacement.

Considering the parts described with reference to Fig. 1 as all properly located in the hole 5, and the latter filled with tamping material if necessary, a squib 14 is introduced into the accessible end of the pipe and lighted, and this squib is of a character which will burn slowly for a sufficient length of time to permit the miners to reach a point of safety. A portion of the squib is filled with powder which will burn in a manner to drive the squib lengthwise of the tube 10 and to and into the open end 4 of the cap 1, setting fire to the detonating material 2 which is of a character to explode violently and so ignite the charge.

There are certain objectionable features to the employment of the tube 10 which are wholly overcome by the structure shown in Figs. 2, 3 and 4. In this arrangement the cap is inclosed in one end of a sheath 8^a which may be considerably longer than the cap, say, twice as long, but is constructed 130

with a tapering end the same as the sheath 8 shown in Figs. 1 and 6. That end of the sheath 8^a remote from the cap is filled with powder 9 as already described, so that such powder may be ignited, and is in fact more readily ignited under the contingencies of use than is the fulminate 2. There is also provided a tube 15 which may be several inches in length and longer than the elongated sheath 8^a, while the taper end of the sheath 8^a is so related to the tube 15 as to enter one end of the latter with the un-tapered or cylindrical end of the sheath 8^a exterior thereto, the external diameter of the cylindrical portion of the sheath 8^a being greater than the internal diameter of the tube 15.

Applied to the exterior of the tube 15 is a bushing 16 preferably of asbestos, and this bushing is of an external diameter such as to fit closely in the drill hole 5. The bushing 16 may be considerably less in length than the length of the tube 15 and is designed to act as an abutment for tamping material, such as indicated at 17 in Fig. 3.

In the mines are implements known as needle rods, and it is the purpose of the present invention to utilize such needle rods by cutting off their extreme taper ends until there is produced a blunt end of about one-fourth of an inch in diameter. Such a needle rod so modified is indicated at 18 in Fig. 4 and a portion of such a rod is shown at 18 in Fig. 2. The tube 15 and the taper end of the rod 18 are so related that the rod 18 will enter the tube 15 for a suitable distance but less than the distance necessary to reach the sheath 8^a, so that there is no chance of friction setting the powder 9 afire. The rod 18 is utilized as a core about which the tamping material 17 may be packed, and this tamping material reaches to the bushing 16, which latter protects the cap from either contact with or displacement by the tamping material. Such tamping material may consist of clay or earth or coal-dust or whatever may be accessible for the purpose, while the bushing 16 presents a refractory and dense abutment far superior to any material heretofore used, and protects the cap from chance sparks. When the tamping material 17 has set the rod 18 is withdrawn and a bore or passage 19 is left leading from the exterior of the drill hole 5 to the outer end of the tube 15. The passage 19 shown in Fig. 3 is comparatively smooth on the interior due to the rod 18, and a squib 14 may be introduced into this bore 19 and on being ignited will travel to the tube 15 and readily enter the same until it reaches the powder 9 which becomes ignited and quickly carries the flame to the detonating material 2 and causes the explosion as before.

With the arrangement shown in Figs. 2 and 3 the liability of a misfire is practically

eliminated and not only is the cap easily and accurately placed, but it cannot become displaced before the explosion.

The present invention provides a means contributing very markedly to the safety of the miners by eliminating certain dangerous practices and conditions which have heretofore prevailed.

What is claimed is:—

1. A blasting cap provided with an external substantially inelastic sheath snugly fitting the cap throughout and having the end remote from the active end externally tapering.

2. A blasting cap provided with an external sheath longer than the cap and externally tapering at the end remote from the active end of the cap, the tapering end having a filling of powder.

3. A blasting cap provided with an external sheath having one end externally tapering, and a tubular carrier for the sheath of a diameter to receive and snugly wedge the tapered end of the sheath when introduced into one end of the carrier.

4. A blasting cap provided with an external and substantially inelastic sheath having the end remote from the active end of the cap externally tapering, in combination with a tube having one end of a diameter to cause the tapering end of the sheath, when introduced into the tube, to wedge therein.

5. A blasting cap provided with a sheath having one end externally tapering, and an elongated tube having one end of an internal diameter to receive and cause the tapering end of the sheath to wedge therein and less than the external diameter of the larger end of the sheath.

6. A blasting cap provided with a sheath longer than the cap and having the end remote from the active end of the cap filled with powder and externally tapering, and a carrier for the cap in the form of a tube of an internal diameter to receive the tapering end of the sheath and less than the external diameter of the larger end of the sheath.

7. A blasting cap provided with a sheath longer than the cap and having the end remote from the active end of the cap filled with powder and externally tapering, and a carrier for the cap in the form of a tube of an internal diameter to receive the tapering end of the sheath and less than the external diameter of the larger end of the sheath, and an external bushing for the tube of a diameter substantially that of the drill hole into which the cap is to be introduced.

8. A blasting cap provided with a sheath longer than the cap and having the end remote from the active end of the cap filled with powder and externally tapering, and a carrier for the cap in the form of a tube

- of an internal diameter to receive the tapering end of the sheath and less than the external diameter of the larger end of the sheath, and an external bushing for the 5 tube of a diameter substantially that of the drill hole into which the cap is to be introduced, said bushing being made fast to the end of the tube into which the cap sheath is introduced.
- 10 9. A blasting cap provided with an external sheath and a carrier therefor having a bore of greater internal diameter than that of the cap and less than that of the sheath and related to the sheath to snugly receive 15 and wedge that end of the sheath remote from the active end of the cap.
- 10 10. A blasting cap provided with a sheath, a carrier in the form of a tube related to the sheath to receive one end thereof snugly, and a bushing for the carrier adapted to the exterior thereof and to the drill hole into which the cap and carrier are to be introduced.
- 20 11. A means for applying blasting caps to charges when lodged in the inner end of a drill hole, comprising a sheath for the cap, a tubular carrier related to the sheath to snugly receive one end thereof with the cap end of the sheath projecting from the carrier, a bushing adapted to the exterior 25 of the carrier, and a core rod having one end
- tapering to enter the end of the carrier remote from that entered by the sheath.
12. A blasting cap having an external sheath prolonged beyond one end of the cap 35 and there filled with powder, and an inelastic tubular member related to the cap and sheath to receive and lodge them tightly at one end of the tubular member against accidental displacement.
13. A means for applying blasting caps to charges when lodged in the inner end of a drill hole, comprising a sheath for the cap, a tubular carrier related to the sheath to snugly receive one end thereof with the cap 40 end of the sheath projecting from the carrier, and a core rod having one end tapering to enter the end of the carrier remote from that entered by the sheath.
14. A blasting cap provided with an external sheath comprising a sheet of suitable material wider at one end than the other and wound upon itself in the direction of its width to provide a tube externally tapering at one end.
- 50 In testimony that I claim the foregoing as my own, I have hereto affixed my signature in the presence of two witnesses.
- 55 JOHN R. POWELL.
- Witnesses:
- JOHN H. SIGGERS,
EDITH L. BROWN.
